O. THIEME.
TABULATING MECHANISM FOR TYPE WRITING MACHINES,
APPLICATION FILED SEPT. 28, 1910.
1,027,225.

Patented May 21, 1912.

UNITED STATES PATENT OFFICE.

OTTO THIEME, OF ST. LOUIS, MISSOURI, ASSIGNOR TO MOON-HOPKINS BILLING MACHINE COMPANY, OF ST. LOUIS, MISSOURI, A CORPORATION OF MISSOURI.

TABULATING MECHANISM FOR TYPE-WRITING MACHINES.

1,027,225.

Specification of Letters Patent.

Patented May 21, 1912.

Application filed September 23, 1910. Serial No. 583,433.

To all whom it may concern:

Be it known that I, OTTO THIEME, a citizen of the United States, residing at St. Louis, Missouri, have invented a certain new and useful Improvement in Tabulating Mechanism for Type-Writing Machines, of which the following is a full, clear, and exact description, such as will enable others skilled in the art to which it appertains to make and use the same, reference being had to the accompanying drawings, forming part of this specification, in which—

Figure 1 is a fragmentary front elevational view showing my improved column stop or tabulating mechanism for typewriting machines. Fig. 2 is a side elevational view of the same, partly in section. Fig. 3 is a top plan view. Fig. 4 is a detail edge view of one of the column stops. Fig. 5 is a detail vertical sectional view through one of the adjustable stops.

This invention relates to tabulating mechanism for typewriting and other machines, and particularly to column stops thereof.

The object is to provide simple and inexpensive means for enabling the machine to be set for different kinds of tabulating work.

In carrying out my invention, there is a series of column stops, each of which is movable in a plane transverse to the rod in which it is mounted into and out of position with respect to the carriage or rack with which it coöperates. These stops are independently adjustable along the rack, and each is provided with means for holding it into and out of its effective position.

In the drawings, 1 indicates the denomination keys mounted upon levers 2, these keys being depressed to lift the rods 3 formed with denomination stops 4 at their upper ends. These denomination stops are preferably cut away at one side or have their upper ends beveled, as shown in Fig. 4, so that when they are raised into position to co-operate with the column stop they will arrest said column stop midway a step or escapement space, whereby, when said stop 4 releases the column stop, said column stop will move thereover so as to be out of the way of the beveled edge of the stop 4, and permit a second operation thereof, and also when the carriage is being returned to its home position, the stop 4, if it should acci-

dentially be left elevated, will be pressed down to its lowered position. 55

Each rod 3 is provided with a shoulder 5 to engage a rack plate 6 mounted on the frame of the machine, whereby, when the rod 3 is raised, plate 6 will be moved back so as to move the upper end of shaft 7 rearwardly. The upper end of shaft 7 carries a pinion 8, which meshes with a rack 9 on the carriage, and said shaft is preferably mounted in a bearing 10, which is normally held in a forward position by means of a spring 11. Shaft 17 carries an escapement wheel 12, which may be of any usual construction. The lower end of shaft 7 is mounted in a step bearing 13, in which is a slight play, so as to permit the movement of 60 its upper end. 70

14 is a ball bearing track on the frame of the machine, with which coöperates carriage track member 15. The front face of this carriage track member is provided with rack 75 teeth 16.

17 is a rod mounted on the carriage adjacent the track member 15, said rod being preferably flattened on its upper face and carrying a scale indicating the space members. 80

18 is a column stop having its rear edge provided with teeth 19 to coöperate with the rack teeth 16. The lower edge of this column stop is provided with a beveled projection 20 for coöperating with the stop plate 4. 85

21 is a handle arranged in the column stop and preferably made hollow so as to contain a spring 22, which normally operates through a follower 22^a upon the flat face of the rod 17 to hold the stop in operative position. When it is desired to adjust the stop longitudinally on the rod 17, the stop is rocked on the shaft 17 so that the teeth 19 are moved in a direction transverse the rack 16 and out of engagement therewith, whereby the said stop may be adjusted longitudinally on the shaft. When adjusted to its proper position, the stop is again rocked on the shaft so as to engage its teeth 19 with the rack. 95 100

I claim:

1. In a tabulating mechanism, the combination of a rod having a flattened portion, column stops mounted to slide upon and oscillate about said rod, said stops comprising 105

a projecting beveled faced member, and a handle member having a spring-pressed follower mounted therein, adapted to engage the flat portion of the shaft to retain the 5 stops in position.

2. In a tabulating mechanism, the combination of a rod, a column stop rotatably and slidably mounted upon said rod, and a denominational stop, said column stop being 10 provided with a stop face, a portion of said stop face lying intermediate said denominational stop and said rod.

3. In a tabulating mechanism, the combination of a carriage and a rack supported 15 thereby, a rod extending along said rack, a column stop mounted upon said rod in such manner as to be capable of being oscillated around and slid upon said rod, said column stop being provided with a stop face, a machine 20 frame upon which said carriage is mounted, and a stop carried by the machine frame, the construction and arrangement of parts being such that a portion of the stop face of the carriage stop is between a portion 25 of said rod and said stop on the machine frame in such manner that pressure exerted on said column stop by means of said stop

carried by the machine frame will be delivered directly upon said rod.

4. In a tabulating mechanism, the combination of a rod, a column stop rotatably and slidably mounted upon said rod, a key operated stop, a stop face upon said column stop, said stop face extending between said rod and said key operated stop and at right angles to the movement of said key operated stop.

5. In a tabulating mechanism, the combination of a rod, a column stop rotatably and slidably mounted upon said rod, a key operated stop, a stop face upon said column stop, said stop face extending between said rod and said key operated stop, and a key for moving said key operated stop in a direction substantially at right angles to said stop face.

In testimony whereof I hereunto affix my signature in the presence of two witnesses, this 12th day of September, 1910.

OTTO THIEME.
